TYPEWRITING MACHINE

John J. Kittel, St. Albans, N. Y., assignor to Royal
Typewriter Company, Inc., New York, N. Y., a
corporation of New York

Application November 12, 1938, Serial No. 240,180

16 Claims. (Cl. 197—63)

This invention relates to typewriting machines, and more particularly to stops for arresting or limiting movement of typewriter carriages in letter-spacing or return directions, and to mechanism for adjustably positioning such stops.

It is usual to provide cooperating stop elements on typewriter main frames and carriages for arresting or limiting movement of the carriages either for fixing the writing margins or for positioning the carriage for tabulating operations.

The illustrative embodiment of the invention to be described comprises a typewriter including stops arranged to arrest movement of the carriage at a predetermined point or predetermined points, and mechanism for adjustably positioning a stop or stops. It will be understood, however, that the invention may be adapted for more general application.

An object is to provide mechanism cooperable with an adjustable stop for quickly and easily moving the stop along its support and automatically setting it in adjusted position.

Another object is to provide mechanism of the character referred to in which the movement of the adjustable stop is controlled by a device supported on the typewriter main frame.

Another object is to provide margin stop setting mechanism by means of which a margin stop may be set in desired carriage-stopping position by merely moving a control device mounted on the main frame without its being necessary first to set the carriage in any particular position on the frame, then moving the carriage to the desired margin position, and then retracting the control device.

Another object is to provide margin stop setting mechanism by means of which a margin stop may be set in desired carriage-stopping position by shifting the carriage to the desired margin position, then moving a control device mounted on the main frame, and then retracting the control device.

A further object is to provide mechanism of the character referred to which is of simple construction, easy to operate, and rapid in its action in correctly positioning the stop.

Other objects will become apparent from a reading of the following description, the appended claims, and the accompanying drawings, in which:

Figure 1 is a fragmentary transverse vertical sectional view of a typewriting machine in which adjustable margin stops are mounted on the carriage and are associated with stop-setting mechanism embodying the invention in one form;

Figure 2 is a vertical sectional view taken on the line 2—2 of Figure 1 with some parts omitted and some parts shown in elevation;

Figure 3 is a fragmentary view mainly in elevation and showing mechanism embodying the invention as it appears when looking from the front toward the rear of the typewriter, and drawn on an enlarged scale;

Figure 4 is a transverse vertical sectional view taken on the line 4—4 of Figure 2 and drawn on an enlarged scale;

Figure 5 is a top plan view of the two adjustable margin stops and associated stop-setting control bails shown in Figures 1 to 4 inclusive;

Figure 6 is a distorted diagrammatic plan view of the resilient stop-urging band and its mounting means shown in Figures 1 to 4 inclusive;

Figure 7 is a view in front elevation of a modification of the embodiment shown in Figures 1 to 5 inclusive;

Figure 8 is a view in front elevation of another modification of the embodiment shown in Figures 1 to 5 inclusive, and drawn on a reduced scale;

Figure 9 is a fragmentary top plan view of a typewriter in which adjustable margin stops are mounted on the main frame and are associated with stop-setting mechanism embodying the invention;

Figure 10 is a fragmentary end elevation looking in the direction of the arrow 10 in Figure 9 and drawn on an enlarged scale;

Figure 11 is a vertical sectional view taken on the line 11—11 of Figure 9 and drawn on an enlarged scale;

Figure 12 is a detailed vertical sectional view taken on the line 12—12 of Figure 9 and drawn on an enlarged scale and with some parts of a left hand margin stop omitted; and

Figure 13 is a fragmentary top plan view of a modification of the embodiment shown in Figures 9 to 12 inclusive.

Mechanism constructed and arranged to operate in accordance with the invention may be embodied in typewriting machines of various kinds.

For typewriters in which adjustable stops are supported on the carriage (Figures 1 to 8 inclusive)

For the purposes of illustration, one form of mechanism embodying the invention is shown in Figures 1 to 8 inclusive as applied to a Royal Standard typewriter. The typewriter shown includes the usual main frame A, carriage B, platen C, combined platen and carriage locating scale D

45

50

55

supported on the carriage, and type bar guide E. The main frame includes a rear wall 1, end walls 2 and 3, and a front wall or cover 4. Mounted on the main frame is an escapement frame 5 supported on a fixed track 6, which, through ball bearings 7, mounts a carriage bearing rail 8 extending between and connecting carriage end plates 9 and 10.

The carriage B is urged to the left in letter 10 space direction by a spring motor (not shown) of a known kind, and is controlled by escapement mechanism supported on the frame 5. The escapement mechanism also may be of a known kind, and only so much of it is shown in the 15 drawings as may be of assistance in understanding the present invention. As shown, the escapement mechanism includes an escapement wheel 11 and an escapement pinion 12 journaled on the frame 5, the pinion 12 being arranged to 20 mesh with a toothed escapement rack 13 carried by a bar 14 mounted on the carriage by means (not shown) permitting the bar and rack 13 to be raised out of engagement with the pinion for rendering the escapement mechanism ineffective.

Central pointers 15 and 16 formed on the type 25 bar guide E cooperate with the scale D for assisting the operator to position the carriage. A center stop 17 of known kind is pivotally mounted as at 18 on the frame wall 1, and a line lock lever 19 is pivotally mounted as at 20 on the center 30 stop 17 in a known manner. A tabular stop mounting assembly F is supported on the carriage, being connected at its opposite ends to the end plates 9 and 10 by studs 21 and 22 respectively.

Adjustable stops are supported and normally 35 locked in fixed position on the carriage for cooperation with the center stop 17 to arrest or limit movement of the carriage, the carriage-mounted stops being urged constantly toward the center stop. Means are provided for quickly and easily 40 unlocking the carriage-mounted stops so as to permit them to be moved by the constant urge until they contact the center stop, after which the carriage is moved to the desired margin positions and the carriage-mounted stops then are 45 locked to the carriage. In the form shown, right and left hand margin stops, respectively designated G and G', are mounted on and for adjustment along a margin stop rod H having transverse teeth 23 spaced along its upper face and being supported on and between the carriage end plates 9 and 10.

The right hand margin stop G includes a tubular body 24 formed with a lateral extension 25 which receives an adjustable abutment screw 26 adapted to cooperate with the line lock lever 19 and center stop 17, a set screw 27 serving to hold the abutment screw 26 in adjusted position. A 50 latch generally designated 28 is pivotally mounted as at 29 on the body 24, and is provided with a nose 30 adapted to fit between adjacent teeth 23 on the margin stop bar H for releasably locking or securing the stop G in adjusted position on 55 the bar H. The latch is formed with a horizontal arm 31 extending toward the center of the carriage, and a spring 32 held in place by a stud 33 is interposed between the body 24 and the horizontal arm 31 for yieldably urging the latch nose 30 toward the teeth 23 of the rod H. A roller 34 60 is mounted on the latch between the pivot 29 and nose 30 and cooperates with mechanism located on the main frame A to release the latch 28. It may be desirable sometimes to release the 65 latch independently of such mechanism, and ac-

cordingly the latch arm is provided with an upstanding finger piece 35, manual depression of which will raise the latch nose, permitting the stop G to be moved along the rack bar.

The construction of the left hand margin stop 5 G' is similar to that of the right hand stop G just described, the only difference being that it is reversed as to right and left hand. Accordingly, no detailed description of the left hand stop G' is necessary. The reversely similar parts 10 of the two stops G and G' are designated by corresponding reference characters, the characters applied to the stop G', however, being primed.

Means are provided for constantly urging both 15 stops G and G' inwardly toward the center of the carriage and towards each other. In the form shown in Figures 1 to 6 inclusive, the stop-urging means comprises a long resilient contractile coil spring band I which advantageously 20 may be of the kind described in detail in the copending application of Henry J. Hart, Serial No. 232,869, filed October 1, 1938, now Patent No. 2,208,367, issued July 16, 1940. One end of the spring I is connected to an ear 36 on the body 25 24 of the stop G, the spring thence extending to the left as at 37, and around a sheave or roller 38 anti-frictionally journaled on a bracket 39 secured to the end plate 10 by a screw 40 so as to rotate about an axis inclined with respect to the axis of rotation of the roller 38. Thence the spring extends to 30 the left as at 42, and is connected to an ear 36' on the body 24' of the stop G'. The length of the spring I is such that, when the stops G and G' are positioned near the center of the carriage, the spring will be in its most contracted position but will be under substantial tension.

To provide the desired free journaling of the rollers 38 and 38', they are mounted by anti-friction ball bearings, the bearings for the right hand roller 38 being shown at 43 in Figure 4. 45 Similar ball bearings, not shown, are provided for freely mounting the left hand roller 38'.

In order to prevent accidental fouling or entanglement of the spring I with adjacent parts, a housing 44 substantially enclosing the entire 50 spring and mounted under the margin stop bar H is secured to the brackets 39 and 39'.

Control means conveniently located on the typewriter are provided for releasing the latch 28 of the stop G so as to unlock the stop from 55 the bar H, permitting the spring I to draw the stop toward the left until arrested by the center stop 17. In the form shown, the control means includes an actuator or bail J which, as viewed in Figure 4, is of generally reversed L shape having rearwardly extending arms 45 and 46 pivotally mounted as at 47 and 48 respectively on the tabular stop assembly F. The bail J includes a horizontally extending ledge or rail 49 which underlies the path of the roller 34 on the stop G. 60 Normally, the bail J is in lowered position with the ledge 49 below and out of contact with the roller 34. A projection 50 on the bail arm 46 cooperates with the stud 21 at the left hand end of the tabular stop assembly F for limiting 70 downward movement of the bail J. The pivotal mounting of the bail permits it to be moved upwardly to bring the ledge 49 into engagement with and to press up on the roller 34 so as to raise the latch nose 28 to release or unlock the 75

stop G from the stop bar H. When the latch is thus released, the spring I will pull the stop G to the left until the abutment screw 26 engages the line lock lever 19. The bail ledge 49 extends 5 parallel to the rack bar H substantially from one end of the carriage to the other so that the bail is adapted to cooperate with the latch roller 34 irrespective of the position of the stop G relative to the carriage and frame.

10 In accordance with one feature of the invention, operating mechanism mounted on the main frame A and normally not operatively connected to the bail J is operable for connecting with and lifting the bail and thereby releasing 15 the latch 28, irrespective of the position of the carriage on the frame. In the illustrative embodiment shown in Figures 1 to 6 inclusive, the operating mechanism includes a reciprocable push link 51 mounted for vertical sliding movements by means of a shouldered screw 52 extending through a slot 53 in the push link and having threaded engagement with a bracket plate 54 secured to the escapement frame 5. A roller 55 journalled on the upper end of the 20 push link 51 is adapted, when the link is raised, to engage the bottom of the bail ledge 49 and swing it upwardly into engagement with and to lift the latch roller 34 to release the latch 28. The lower end of the link 51 is pivotally connected as at 56 to one arm 57 of a lever 58 which 25 is pivoted as at 59 on the frame rear wall 1. The other arm 60 of the lever 58 is received by the bifurcated end 61 of one arm 62 of a bell crank lever 63 pivotally mounted as at 64 30 on the frame side wall 3. The other arm 65 of the lever 63 is pivotally connected as at 66 to a thrust bar 67 which extends forwardly from the rear part of the typewriter and passes through and beyond an opening 68 in the frame 35 front wall 4, the bar 67 being provided at its outer end with a finger key 69. Preferably, the push bar 67 is formed with an offset or vertically extending portion 70 adapted to abut against the inner face of the front wall or cover 4 to 40 limit forward movement of the push bar, and consequently to limit movement of the lever 63, the lever 58, and the push link 51 under the urge of a spring 71 connected between a stud 72 on the lever 58 and an ear 73 on the main frame. 45

50 It is apparent that, by pushing the bar 67 rearwardly, the lever 63 will be rocked in a clockwise direction as viewed in Figure 1, the lever 58 will be rocked in a clockwise direction as viewed in Figure 2, and the push link 51 will be raised. 55 The bar device 67 is formed with a notch 74 adapted to receive the upper edge of the opening 68 to permit the bar to be releasably set or locked in pushed-in position.

When it is desired to set the margin stop G in 60 a position in which it will maintain a right-hand margin equivalent to, say, seventy letter spaces on the typed sheet, the push bar 67 will be pushed rearwardly so as to rock the bell crank lever 63 in a clockwise direction as viewed in Figure 1 65 and to rock the lever 58 in a clockwise direction, as viewed in Figure 2, so as to raise the lift link 51. As the lift link 51 is raised, the roller 55 at the top of the lift link will engage the ledge 49 of the bail J so as to swing the bail upwardly, causing the ledge 49 to engage and lift the roller 34 on the latch 28, thereby disengaging the latch nose 30 from the toothed bar H. The push rod 67 may be releasably locked in its pushed-in or 70 latch-releasing position by raising it slightly, so 75 that the upper edge of the opening 68 is received

in the notch 74, thus rendering it unnecessary for the operator to hold the push rod inwardly against the urge of the spring 71 while the carriage is being shifted to the desired margin position. The spring I then will draw the margin 5 stop G to the left until it is arrested by the line lock lever 19 and center stop 17. If the carriage B is moved either to the right or to the left, the stop G will be held up against the line lock lever and center stop by the spring I. To "set" 10 the stop G, the carriage is moved to the position in which the marking "70" on the bottom of the scale D registers with the pointer 18 on the type bar guide E if the typewriter is set for lower case typing, or registers with the pointer 15 on the 15 type bar guide E if the typewriter is set for upper case typing. After the carriage has been moved to this position, the push rod 67 is retracted, thereby permitting the lift link 51 to be lowered by the spring 71 and causing the bail J to move 20 down to the position shown in Figure 4, so as to permit the nose 30 of the latch 28 to engage the toothed bar H, thereby locking the stop G in the desired position. It is apparent that, if the carriage thereafter is moved to the left during the 25 typing of a line, the abutment screw 26 on the stop G will engage the line lock lever 19 which, in connection with the center stop 17, will arrest movement of the carriage and fix the margin at 30 seventy letter spaces.

Similar control means is provided for releasing the latch 28' of the margin stop G' to permit setting of the latter for fixing the desired left-hand margin. The control means associated with the stop G' includes a bail J', which, as viewed in 35 Figure 4 is reversed with respect to the bail J, that is, it is of L shape, whereas the bail J is of reversed L shape as previously stated. Also the arms 45' and 46' of the bail J' are somewhat longer than the arms 45 and 46 of the bail J, so 40 as to position the bail J' in front of the bail J. Operating mechanism associated with the bail J' includes a lift link 51', lever 58', lever 63', and push bar 67', all of which are similar in construction and relative arrangement to the lift link 51, lever 63, lever 58, and push bar 67, previously described. Accordingly no detailed description of the bail J' and associated operating mechanism is necessary. The parts of the bail J' and associated mechanism are designated by reference 45 characters corresponding to those designating similar parts of the bail J and its associated operating mechanism, the reference characters applied to the parts of the bail J' and associated mechanism however, being primed. The operation of the push bar 67', the bail J', and associated mechanism for releasing the latch 28' is 50 similar to the operation of the push bar 67 and bail J for releasing the latch 28. It may be noted, however, that the abutment screw 26' on 55 the stop G' is adapted to engage directly with a buffer 75 pivotally mounted as at 20 on the line lock lever, a buffer spring 76 connected to the buffer 75 and to the center stop 17 (at a point not shown) serving to cushion the impact of the 60 stop G' against the center stop.

Assuming that it is desired to set the left hand margin at twenty letter spaces, and the right hand margin at seventy letter spaces, both push bars 67 and 67' will be pushed rearwardly, thereby releasing the latches 28 and 28' and permitting the spring I to pull the stops G and G' into engagement respectively with the line lock lever 19 and the buffer 75, which, in cooperation with the center stop 17, will hold the stops G and G' 65 70 75

against further movement under the urge of the spring I. The carriage may then be moved until the pointer 15 or 16 registers with the marking "20" on the bottom of the scale D, and the push bar 67' is then released so as to permit it to move forwardly, thus effecting the locking of the stop G' in fixed position on the rod H by means of the latch 28'. The carriage B may then be moved until the pointer 15 or 16 registers with the marking "70" on the bottom of the scale D, and the push bar 67 is released and moved forwardly so as to effect locking of the stop G to the bar H by means of the latch 28. The two stops G' and G will then be set so as to maintain the proper left hand and right hand margins on the typed sheets.

Alternatively, the stops may be set in the following manner. First, the push bars 67 and 67' are pushed rearwardly to release the latches 28 and 28'. The carriage is then moved to its extreme right hand position, which will effect positioning of the stop G' at its extreme outer or left hand position on the rod H. The push rod 67' is then moved forwardly to effect locking of the stop G' to the rod H. Thereafter, the carriage is moved to its extreme left hand position so as to locate the stop G adjacent the right end of the rod H, and the push rod 67 is then returned to its forward position to effect locking of the stop G to the rod H. Then the carriage is moved until the pointer 15 or 16 registers with the lower scale marking "20," and the push rod 67' is pushed rearwardly to unlatch the stop G' so as to permit the spring I to pull the stop G' to the right until arrested by the buffer 75 and the center stop 17. The lever 67' will then be returned to its forward position to effect locking of the stop G' to the margin stop rod H in the desired position. The carriage is then moved to the left until the pointer 15 or 16 registers with the lower scale marking "70," and the push rod 67 is pushed rearwardly so as to unlatch the stop G and permit the spring I to draw the stop G to the left until it is arrested by the line lock lever 19 and the center stop 17. Finally the push rod 67 is returned to its forward position, effecting locking of the stop G to the bar H in the desired position.

The modified embodiment of the invention shown in Figure 7 is particularly adapted for use in connection with typewriters having very long carriages, but may also be used with carriages of the usual length. Figure 7 shows the invention as embodied in connection with a long carriage 55 B which may, except as regards its length, be similar to the carriage shown in Figures 1 to 6 inclusive. Accordingly parts of the carriage, the margin stops, and stop-operating mechanism shown are designated by reference characters the 60 same as the characters designating corresponding parts in Figures 1 to 5 inclusive. In the modification, a spring motor powered drum or barrel 77 is journaled as at 78 on the left hand end of the carriage, and a cord or flexible band 79, which 65 may itself be non-expansible, is partially wound on the drum and has an unwound end portion 80 extending past the left margin stop G', and is connected to the ear 36 on the right margin stop G. Similarly, a spring motor powered drum or 70 barrel 77' is journaled as at 78' on the right hand end of the carriage, and a cord or band 79' partially wound on the drum 77' has its unwound end portion extending past the right margin stop G for connection to the ear 36' on the left margin stop G'. The arrangement is such that the

drums 77 and 77' respectively urge the stops G and G' toward the center stop 17. Positioning and locking of the margin stops in adjusted positions may be effected with the cooperation of suitable control mechanism such as the mechanism described above with reference to Figures 1 to 5 inclusive.

In the modification shown in Figure 8 only the left hand margin stop G' is adapted to be set by mechanism such as that previously described by the right hand stop K being set manually. Such an arrangement is satisfactory for many classes of work wherein one margin on the typed sheet does not have to be reset as frequently as is necessary with respect to the other margin. In this embodiment a spring motor powered barrel or drum 81 is shown as being journaled as at 82 on the left hand end of the carriage B. A cord or band 83, which itself may be non-expansible, is partially wound on the drum and has its unwound end portion extending to the right past the margin stops G' and K as at 84, then around a pulley 85 journaled as at 86 on the carriage end plate 10, and then is extended back to the left as at 87, past the margin stop K for connection to the ear 36' on the margin stop G'. The arrangement is such that the barrel or drum 81 constantly urges the stop G' toward the center stop. Positioning and locking of the stop G' in adjusted position may be effected with the cooperation of suitable control mechanism such as the mechanism described above, with reference to Figures 1 to 5, inclusive. A right hand margin stop K is mounted for adjustment along the toothed bar H and is provided with a latch 88 pivotally connected as at 89 to the latch body and having a nose 90 adapted to engage teeth on the bar H. A spring 91 urges the latch nose into engagement with the teeth, and a finger piece 92 extending well above the bail J provides for easy manipulation of the latch during manual positioning of the stop K.

For typewriters in which adjustable stops are supported on the main frame (Figures 9 to 13 inclusive)

Figures 9 to 12 inclusive show a form of stop-setting mechanism embodying the invention and adapted more particularly for use in typewriters having adjustable margin stops carried by the main frame and cooperating stop means fixed to the carriage. Only such of the usual or known typewriter structure as may be of assistance in understanding this embodiment of the invention is shown. The known structure includes a main frame L on which a carriage M equipped with a platen or cylinder N is mounted for letter-spacing and return movements. A pointer O fixed to the carriage cooperates with a carriage-positioning scale P mounted on the main frame for indicating the letter space position of the carriage. A lever 101 pivotally mounted as at 102 on the carriage M is provided at its right hand end with an upstanding finger piece 103, and at its left hand end is formed with a projecting stop 104 which cooperates with a projection 105 on a margin stop generally designated Q mounted to slide on a front tie rod R and a rack bar S, both mounted on the main frame. The margin stop Q cooperates with the stop projection 104 on the carriage for fixing the left hand margin on the typed sheet when the carriage is moved to the right. By depressing the finger piece 103, the lever 101 may be swung to move the projecting stop 104 upwardly, so that it may clear the stop 105 to 75

effect left margin release. Another stop projection 106 fixed to the carriage is adapted to cooperate with a stop plate 107 on a margin stop T mounted to slide on the front tie rod R and a rack bar U, both carried by the main frame, so as to fix the right hand margin on the typed sheet when the carriage is moved to the left. The margin stops may be provided with pointers (not shown) adapted to cooperate with the scale 10 P for assisting in determining the positions in which the stops should be set in order to fix desired margins on the typed sheet.

In accordance with the present invention, the margin stops Q and T are so constructed and arranged as to be urged respectively towards the stops 104 and 106 under the control of mechanism entirely carried by the main frame. The urging of the stops Q and T is effected, in the form shown in Figures 9 to 12 inclusive, by a spring band V which is connected at one end as at 108 to the margin stop Q, thence extending to the left as at 109 around a pulley 110 journaled at 111 on the main frame, thence to the right as at 112 and around a pulley 113 journaled as at 114 on the main frame, and thence to the left as at 115 for connection as at 116 to the margin stop T. The long coil spring V is always under tension, and constantly urges the margin stop Q toward the stop projection 104, and constantly urges the margin stop T toward the stop 106.

To releasably secure the stop Q in adjusted position on the frame against the urge of the spring V, a latch 117 is pivotally mounted as at 118 on the stop Q and is provided with a nose 119 constantly urged into engagement with teeth on the bar S by means of a spring 120 interposed between an arm 121 on the latch and an abutment 122 on the body of the stop Q. A finger piece 123 fixed to the arm 121 is provided for manually releasing the latch 117, and a roller 124 journaled on the arm 121 cooperates with mechanism, to be described, for releasing the latch to permit the spring V to draw the stop toward the left. The mechanism for operating the latch is mounted entirely on the main frame, and includes a bail or tracker bar 125 which extends longitudinally of the main frame and normally is disposed substantially in a vertical plane. The tracker bar 125 is provided with mounting arms 126 and 127 which are pivoted respectively as at 128 and 129 on brackets 130 and 131 on the main frame. The arm 127 is offset as at 132 and is provided with a longitudinal extension 133 terminating at its end in a vertical extension 134 at the top of which is a forwardly projecting finger lever device 135. A spring 136 interposed between the vertical extension 134 and a limiting stop 137 urges the tracker bar to the position shown in Figures 9, 10, and 11, wherein it is out of contact with the roller 124.

In operation, when it is desired to fix the left hand margin on the typed sheet, the finger lever 135 is depressed so as to rock the tracker bar in a counterclockwise direction as viewed in Figure 11, thereby causing the upper portion of the tracker bar to engage the latch roller 124, moving it to the left as viewed in Figure 11, and thereby disengaging the latch nose 119 from the toothed rack bar S. Disengagement of the latch from the bar S will result immediately in movement of the margin stop Q toward the left under the urge of the spring V until the stop projection 105 on the margin stop Q engages and is arrested by the stop projection 104 on the carriage. The carriage is then moved to the desired

margin position, and the finger lever 135 is released, permitting the spring 136 to return the tracker bar to the position shown in Figures 9, 10, and 11, thus allowing the spring 120 to move the latch nose 119 into engagement with the rack bar S, thereby locking the stop Q in position for fixing the left hand margin at the desired point. In the normal or state of rest position of the tracker bar 125, a considerable clearance or space is provided between the bar and the roller 124, thus preventing accidental releasing of the latch 117.

To releasably secure the stop T in adjusted position on the main frame against the urge of the spring V, a latch 138 is pivotally mounted as at 139 on the margin stop T, and is provided with a nose 140 urged into engagement with the toothed bar U by means of a spring 141. The latch is provided with an arm 142 at the outer end of which is a finger piece 143 by means of which the latch may be manually released when it is desired to set the margin stop T manually. Also at its outer end, the arm 142 is provided with a roller 144 adapted to cooperate with a bail or tracker bar 145 for releasing the latch under the control of mechanism entirely carried by the main frame. The tracker bar 145 extends longitudinally of the main frame and is formed with mounting arms 146 and 147 pivotally mounted as at 148 and 149 respectively on the main frame brackets 130 and 131. The arm 146 is offset as at 150, and is formed with a longitudinal extension 151 at the end of which is a return offset 150 having at its end a vertical extension 151 terminating in a rearwardly projecting finger lever device 152. A spring 153 interposed between the vertical extension 151 and a pin 154 on the main frame urges the tracker bar 145 against a limiting stop 155 on the main frame. In this position, the tracker bar will be disposed substantially in a vertical plane as shown in Figures 9 to 12 inclusive.

In operation, when it is desired to set the right hand margin on the typed sheet at any desired point, the finger lever 152 is depressed so as to rock the tracker bar 145 in a clockwise direction as viewed in Figures 10, 11, and 12, causing it to engage the roller 144 on the latch 138 and to release the latch nose 140 from engagement with the rack bar U. Thus the spring V will draw the margin stop T toward the right until the stop plate 107 on the margin stop T engages the stop projection 106 on the carriage. Then the carriage is moved to the desired right hand margin position, and the finger lever 152 is released, permitting the tracker bar 145 to return to the position shown in Figures 10 to 12 inclusive, thus allowing the latch 138 to be moved to latching position by the spring 141. In this way the stop T will be locked in position on the main frame for maintaining the desired right hand margin on the typed sheet. It will be observed that, when the tracker bar 145 is in its normal or state of rest position as shown in Figures 10 to 12 inclusive, there is considerable clearance or space between the tracker bar and the roller 144. Such clearance assures that there can be no accidental disengagement of the latch 138 through vibration of the parts.

Figure 13 shows a modified form of stop-setting means which may be used in connection with a typewriter in which adjustably positioned margin stops are mounted on the main frame. In accordance with this modification, a spring motor powered drum 156 is journaled on the main

frame as at 151, and a band or cord 153, which itself may be non-expansible, is wound partially on the drum 156, and has an unwound portion extending to the right as at 159 and around a pulley 160 journaled as at 161 on the margin stop Q, the band or cord thence extending toward the left as at 162 for connection at 163 to the margin stop T. The drum 156 constantly exerts a pull on the stretches 159 and 162 of the cord or band, whereby the stop Q is urged toward the left, and the stop T is urged toward the right as viewed in Figure 13. Thus the powered barrel or drum 156 cooperates with the band or cord 153 for urging the stops T and Q in a manner similar to that effected by the spring V incorporated in the embodiment shown in Figures 9 to 12 inclusive. Otherwise construction and operation of the margin stops Q and T and related elements shown in Figure 13 are similar to the construction and operation of the margin stops and their related elements described with reference to Figures 9 to 12 inclusive, and therefore need not be referred to in detail.

The rack bar U is provided with arms 164 and 165 which mount the bar U for limited rocking movements about the front tie rod R for operating bell-ring and line lock mechanism (not shown). The bar U is urged to its normal position by a spring X, movement of the bar under the urge of the spring being limited by a stoppin Y.

The finger levers 155 and 152 are shown as being located on the main frame L between the carriage M and key board W. This location is preferred because of its proximity to the key board, and consequent convenience.

Figures 1 to 13 inclusive

In all of the embodiments illustrated, the latch actuators or bails are cooperable with the latches irrespective of the positions of the margin stops relative to the frame. Although the manually operable latch-releasing devices are constrained against movement with respect to the frame in the direction of carriage letter-spacing movement, they are cooperable with the actuators, bails, or tracker bars irrespective of the position of the carriage with respect to the frame. Thus the margin stop or stops may be set very easily merely by manipulating a device on and at the front of the frame and by moving the carriage.

The mechanisms disclosed herein embody the invention in practical and the now preferred forms, but it will be understood that various changes may be made without departing from the invention claimed.

I claim:

1. In a typewriter, a frame; a carriage mounted thereon for letter spacing and return movements; a stop on said frame; a cooperating stop adjustably mounted on said carriage for movement to selected positions thereon in the direction of said movement of the carriage; releasable means for securing said carriage-mounted stop in adjusted position on the carriage; and operating means cooperable with said securing means irrespective of the position of the carriage-mounted stop relative to the frame for releasing said securing means, said operating means including a carriage-mounted releasing member adapted to be moved relatively to the carriage and into engagement with said securing means for releasing the latter, and a manually operable device mounted on the frame and being adapted to be operatively

connected to said releasing member for so moving the latter into engagement with said securing means, said manually operable device being constrained against movement with the carriage.

2. In a typewriter, a frame; a carriage mounted thereon for letter spacing and return movements; a stop on said frame; a cooperating stop adjustably mounted on said carriage for movement to selected positions thereon in the direction of said movement of the carriage; releasable means for securing said carriage-mounted stop in adjusted position on the carriage; an actuator mounted on the carriage and cooperable with said securing means for releasing the latter irrespective of the position of the carriage-mounted stop on the carriage; and operating means mounted on the frame and being cooperable with said actuator irrespective of the position of the carriage on the frame.

3. In a typewriter, a frame; a carriage mounted thereon for letter spacing and return movements; a stop on said frame; a cooperating stop adjustably mounted on said carriage for movement to selected positions thereon in the direction of said movement of the carriage; means constantly urging said carriage-mounted stop towards said frame-mounted stop; releasable means for securing said carriage-mounted stop in adjusted position on the carriage; and operating means cooperable with said securing means irrespective of the position of the carriage-mounted stop relative to the frame for releasing said securing means, said operating means including a carriage-mounted releasing member adapted to be moved relatively to the carriage and into engagement with said securing means for releasing the latter, and a manually operable device mounted on the frame and being adapted to be operatively connected to said releasing member for so moving the latter into engagement with said securing means, said manually operable device being constrained against movement with the carriage.

4. In a typewriter, a frame; a carriage mounted thereon for letter spacing and return movements; a stop on said frame; a cooperating stop adjustably mounted on said carriage for movement to selected positions thereon in the direction of said movement of the carriage; means constantly urging said carriage-mounted stop towards said frame-mounted stop; releasable means for securing said carriage-mounted stop in adjusted position on the carriage; an actuator mounted on the carriage and cooperable with said securing means for releasing the latter irrespective of the position of the carriage-mounted stop on the carriage; and operating means mounted on the frame and being cooperable with said actuator irrespective of the position of the carriage on the frame.

5. In a typewriter, a frame; a carriage mounted thereon for letter spacing and return movements; a stop on said frame; a cooperating stop adjustably mounted on said carriage for movement to selected positions thereon in the direction of said movement of the carriage; releasable means for securing said carriage-mounted stop in adjusted position on the carriage; operating means cooperable with said securing means irrespective of the position of the carriage-mounted stop relative to the frame for releasing said securing means, said operating means including a carriage-mounted releasing member adapted to be moved relatively to the carriage and into en-

gagement with said securing means for releasing the latter, and a manually operable device mounted on the frame and being adapted to be operatively connected to said releasing member 5 for so moving the latter into engagement with said securing means, said manually operable device being constrained against movement with the carriage; and releasable locking means associated with said manually operable device for 10 maintaining said releasing member in position to maintain said securing means in released position.

6. In a typewriter, a frame; a carriage mounted thereon for letter spacing and return movements; 15 a stop on said frame; a cooperating stop adjustably mounted on said carriage for movement to selected positions thereon in the direction of said movement of the carriage; means constantly urging said carriage-mounted stop towards said frame-mounted stop; releasable means for securing said carriage-mounted stop in adjusted position on the carriage; an actuator mounted on the carriage and cooperable with said securing 20 means for releasing the latter irrespective of the position of the carriage-mounted stop on the carriage; and control means including a manually operable element movably mounted on said frame and being adapted when moved to be operatively 25 connected to said actuator irrespective of the position of the carriage on the frame and to move the actuator and thereby release the securing means, and means cooperable with said manually operable element for releasably retaining the 30 manually operable element in the position to which it has thus been moved.

7. In a typewriter, a frame; a carriage mounted thereon for letter spacing and return movements; 40 a stop on said frame; a cooperating stop adjustably mounted on said carriage for movement to selected positions thereon in the direction of said movement of the carriage; a latch on said carriage-mounted stop for releasably securing it in adjusted position on said carriage; means for 45 moving said carriage-mounted stop on said carriage when the latch is released; a member mounted on said carriage and extending in the direction of adjusting movement of the carriage-mounted stop and being cooperable with said latch 50 irrespective of its position on the carriage for releasing the latch; and frame-mounted means constrained against movement with the carriage and being cooperable with said member irrespective of the position of the carriage on the frame 55 for operating said member to effect releasing of the latch.

8. In a typewriter, a frame; a carriage mounted thereon for letter spacing and return movements; 60 a center stop on said frame; a toothed margin stop bar mounted on the carriage; right and left-hand margin stops mounted on and for adjustment along said bar respectively on opposite sides of said center stop; latches respectively mounted 65 on said margin stops for cooperation with teeth on the bar to retain the margin stops in adjusted position; carriage-mounted latch-actuating means extending in the direction of movement of the margin stops on the bar and adapted to operatively engage the margin stop latches selectively 70 in different positions of the margin stops on the bar; and frame-mounted means cooperable with said latch-actuating means irrespective of the position of the carriage on the frame for releasing the latches selectively, said frame-mount- 75

ed means being constrained against movement with said carriage.

9. In a typewriter, a frame; a carriage mounted thereon for letter spacing and return movements; 5 a center stop on said frame; a toothed margin stop bar mounted on the carriage; right and left hand margin stops mounted on and for adjustment along said bar respectively on opposite sides of said center stop; latches respectively mounted on said margin stops for cooperation with teeth on the bar to retain the margin stops in adjusted position; carriage-mounted latch-actuating means extending in the direction of movement of the margin stops on the bar and adapted to operatively engage the latches in different positions 15 of the margin stops on the bar; and means for operating said latch-actuating means supported entirely on the frame and normally being operatively disconnected from said latch-actuating 20 means.

10. In a typewriter, a frame; a carriage mounted thereon for letter spacing and return movements; a center stop on said frame; a toothed margin stop bar mounted on the carriage; right 25 and left hand margin stops mounted on and for adjustment along said bar respectively on opposite sides of said center stop; latches respectively mounted on said margin stops for cooperation with teeth on the bar to retain the margin stops 30 in adjusted position; two carriage-mounted bails extending in the direction of movement of the margin stops on the bar and adapted to engage the margin stop latches respectively in all positions of the margin stops on the bar; and bail-operating means supported entirely on the frame 35 and normally being operatively disconnected from said bails, said bail-operating means including a pair of reciprocable links adapted respectively to engage and operate said bails to release the associated latches irrespective of the position of the 40 carriage on the frame.

11. In a typewriter, a frame; a carriage mounted thereon for letter spacing and return movements; a center stop on said frame; a toothed margin stop bar mounted on the carriage; right 45 and left hand margin stops mounted on and for adjustment along said bar respectively on opposite sides of said center stop; latches respectively mounted on said margin stops for cooperation with teeth on the bar to retain the margin stops 50 in adjusted position; two carriage-mounted bails extending in the direction of movement of the margin stops on the bar and adapted to engage the margin stop latches respectively in all positions of the margin stops on the bar; and bail-operating means supported entirely on the frame 55 and normally being operatively disconnected from said bails, said bail-operating means including a pair of reciprocable links equipped with rollers 60 adapted respectively to engage and operate said bails to release the associated latches irrespective of the position of the carriage on the frame.

12. In a typewriter, a frame; a carriage mounted thereon for letter spacing and return 65 movements; a center stop on said frame; a toothed margin stop bar mounted on the carriage; right and left hand margin stops mounted on and for adjustment along said bar respectively on opposite sides of said center stop; 70 latches respectively mounted on said margin stops for cooperation with teeth on the bar to retain the margin stops in adjusted position; two carriage-mounted bails extending in the direction of movement of the margin stops on the bar 75

and adapted to engage the margin stop latches respectively in all positions of the margin stops on the bar; bail-operating means supported entirely on the frame and normally being operatively disconnected from said bails, said bail-operating means including a pair of reciprocable links adapted respectively to engage and operate said bails to release the associated latches irrespective of the position of the carriage on the frame; and manually operable members respectively connected to said links and extending to the front part of the frame.

13. In a typewriter, a frame; a carriage mounted thereon for letter spacing and return movements; a stop on said frame; a toothed margin stop bar on the carriage; a stop mounted on and for adjustment along said bar; a latch mounted on said carriage-mounted stop for co-operation with teeth on the bar to retain the carriage-mounted stop in adjusted position; a carriage-mounted bail extending parallel to the bar and below the line of movement of a part of said latch; means mounting the bail for movement upwardly to disengage the latch from the bar; and frame-mounted means engageable with the bail irrespective of the position of the carriage on the frame for lifting the bail.

14. In a typewriter, a frame element; a carriage element mounted thereon for letter spacing and return movements; a bar mounted on one of said elements extending in the direction of carriage movement; a margin stop mounted on and for adjustment along said bar; a member under tension connected to the bar-mounting element at one end of the bar and extending parallel to said bar past said margin stop, around a part fixed to said bar-mounting element at the other

end of said bar and being attached to said margin stop; and means associated with said margin stop for releasably securing it to said bar.

15. In a typewriter, a frame element; a carriage element mounted thereon for letter spacing and return movements; a bar mounted on one of said elements extending in the direction of carriage movement; a margin stop mounted on and for adjustment along said bar; a power-operated drum rotatably mounted on the bar-mounting element at one end of the bar; a roller mounted on a fixed axis on the bar-mounting element at the other end of the bar; a band partially wound on said drum and having an unwound stretch extending past said margin stop, around said roller, and back parallel to said bar and having its unwound end attached to said margin stop; and means associated with said margin stop for releasably securing it to said bar.

16. In a typewriter, a frame; a carriage mounted thereon for letter spacing and return movements; a stop on said frame; a toothed margin stop bar on the carriage; a stop mounted on and for adjustment along said bar; a latch mounted on said carriage-mounted stop for co-operation with teeth on the bar to retain the carriage-mounted stop in adjusted position; a carriage-mounted rail extending parallel to the bar and adjacent the line of movement of a part of said latch; means mounting the rail for movement towards the line of movement of the latch to disengage the latch from the bar; and frame-mounted means adapted to be operatively connected to the rail irrespective of the position of the carriage on the frame for so moving the rail.

JOHN J. KITTEL.
